UNITED STATES PATENT OFFICE.

ROBERT A. GOELLER, OF LARCHMONT, NEW YORK.

CONNECTER.

Application filed October 1, 1926. Serial No. 138,856.

This invention relates to a terminal or connector of an electrical conductor and particularly to a terminal or connector adapted to have a gripping action on the surface of 5 the conductor.

The object of the invention is to provide a connector which will be simple in a form and action and effective to give a secure hold with very intimate electrical contact between 10 the parts.

Fig. 1 is a fragmentary sectional view of my improved connector in its open position,

Fig. 2 is a similar view of the connector in connected position,

Fig. 3 is a sectional view showing my improved connector for holding two oppositely extending conductors together, and

Fig. 4 is a sectional view of my improved connector illustrating a modification.

Prior connectors having rotatable gripping jaws have required the conductor to move or twist with the jaws during the gripping action, or, if the conductor did not move with the jaws, the grip and contact 25 would be impaired by the slippage between the parts. When a conductor is thus twisted during fastening its constant tendency is to untwist and loosen the parts in very objectionable manner.

The connecting means of this invention overcomes these objections and does not require the conductor to move or twist with the gripping jaws, but on the contrary gives a gripping cutting action of the jaws by their 35 rotations around and movements along the conductor, the jaws being specially formed to cut a helical thread into the conductor during the gripping action to attain a very strong mechanical grip and a most intimate

electrical contact.

In the embodiment of my invention illustrated in the drawings a conically tapered wedge socket 5 is formed in a socketed sleeve or conductor-receiving member 4, which 45 member is provided with a generally cylindrical threaded seat or socket portion 6. The gripping member is in the form of a nut with locking jaws and comprises a body portion 7 threaded to screw into the threaded 50 portion 6 and carrying the jaws 8 which cooperate with the tapered socket 5. The jaws 8 are preferably formed as shown by tapered slots 9 and are of resilient, hardened material.

The outer surface 10 of the jaws 8 is conically tapered as shown in Fig. 1 to an angle

with the axis of the cone slightly less than the angle of taper of the wedge socket 5 and as the gripping member is screwed into the socket the bending of the jaws will bring 60 their conical surface more and more to the taper of the socket portion 5 as indicated in Fig. 2.

The gripping member has a generally cylindrical opening 11 through it, with the end 65 of the jaws threaded by a tapered threading die producing threads 12 which progressively decrease in depth from the outer ends of the jaws toward their base, the apexes of the threads being along the generally cylindrical surface of the opening 11.

In operation the conductor 13 is inserted 70 through the open jaws as indicated in Fig. 1 and may have its end positioned against a bottom or end wall 14 of the socket. Then 75 upon screwing in the gripping member, the conductor remaining stationary with relation to the socket, the threads 12 will gradually cut into the conductor. The pitch and direction given to the threads 12 with relation to threads 6, 7 are such that the gripping member will screw onto the conductor at the same rate that said member screws into the socket, and the gripping member thus screws into the socket and onto the conductor 80 at the same time while the conductor and socket remain fixed with relation to each other.

The threading jaws 8 thus cut fresh surfaces of contact which are very extensive in 90 area as compared with the line contacts of the prior art. The surfaces are also pressed and wedged together very tightly, there being an actual screw connection between the jaws and the conductor. The conductor not 95 having twisted during the fastening operation has no tendency to untwist and any strains imposed upon the conductor in the direction of unscrewing it will be resisted by the end 15 gripped between the jaws and the end wall 14. In order for the conductor 100 to unscrew out of the jaws it would be necessary for a twisting force to be in the unscrewing direction and sufficient in force to cut a deep thread through the end 15. A 105 straight pull on the conductor could not release it without stripping the cut threads and also the end 15. The gripping member may be locked in its socket by any desired locking means such as a set screw 16.

In Fig. 3 the invention is shown applied 110 to a coupling permitting conductors, extend-

ing in opposite directions, to be connected, the gripping member being shown provided with a wrench head 17.

In Fig. 4 a double connection is shown so as to reinforce the first connection thereof, and is particularly applied to a T connection, although the T does not form a part of the present invention. The socketed sleeve or socket member 20 has threaded connection 10 with a T head 21 and is provided with a tapered socket 22 and threaded portion 23. The jaws 24 extend forwardly from the sleeve 25 while a second socket member 26 extends rearwardly from the sleeve 25, there 15 being provided a tapered surface 27 for receiving the jaws 18 of the type of clamping member shown in Fig. 1. The threads formed on the inner sides of the jaws 18 and 24 are of a pitch corresponding to the 20 threads formed on the sleeve 20 and socket 26 so that the same principle of operation as previously described is present in the assembling of the connector and conductor. The jaws 24 will be made to grip first the 25 conductor, after which the jaws 18 will be brought into operative relation to the conductor. Due to this double arrangement a very substantial support is provided for the conductor and any possible strain on the 30 threads of jaws 24 will be materially lessened. Under no condition, however, will the threads cut in the conductor by the jaws be weakened or stripped during the clamping action as is possible in those types of 35 prior art connectors before mentioned.

I claim:

1. An electrical connector comprising a member to receive a conductor, and means for holding said conductor relative to said 40 member comprising a sleeve device threaded to said member and clamping jaws actuated by said sleeve device and adapted to cut into the body of said conductor and rotate relative thereto while permitting a normal cutting relation between said jaws and conductor.

2. An electrical connector comprising holding jaws having helical screw threads,

and means for forcing said threads into the body of the conductor including cooperating 50 screw threads of the same pitch as said cutting threads whereby during the cutting action said cutting threads will travel along said conductor at the same rate as said cooperating screw threads move relative to 55 each other.

3. An electrical connector comprising a plurality of means for cutting into the body of a conductor to hold the same, one of said means having helical screw threads 60 for cutting into the body of the conductor, and means for effecting said cutting action including cooperating screw threads having the same pitch as said cutting threads.

4. An electrical connector comprising 65 a plurality of means for cutting into the body of a conductor to hold the same, one of said means having helical screw threads for cutting into the body of the conductor, and means for effecting said cutting action in- 70 cluding cooperating screw threads having the same pitch as said cutting threads, said second cutting means being supported by said first mentioned means.

5. A connector for an electrical conductor 75 comprising a solid body portion having a tubular end socket adapted to receive the end of the conductor, and means for fastening said conductor in said socket comprising means rotatable with relation to the conductor and the body portion and having interior surface projections adapted to bite into the conductor, and a threaded portion threaded to the body portion to turn and force the 80 parts together.

6. An electrical connector comprising a member to receive a conductor, a means for holding said conductor relative to said member, comprising a sleeve device threaded to said member and clamping jaws, actuated by said sleeve device and member to cut into the body of said conductor with increasing depth and move relative thereto as the sleeve device rotates.

ROBERT A. GOELLER.
